(57) **CLAIM**

I claim the ornamental design for glove box, as shown and described.

DESCRIPTION

FIG. 1 is a isometric top view of glove box showing of our new design;

FIG. 2 is a bottom view of glove box thereof;

FIG. 3 is a top view of glove box without cover plates thereof;

FIG. 4 is an end view of glove box thereof;

FIG. 5 is a front view of glove box thereof;

FIG. 6 is a left side view of glove box thereof; and,

FIG. 7 is a right view 6 of glove box thereof.

The broken lines are included for the purpose of illustrating a portion of the glove box that forms no part of the claimed design.

1 Claim, 5 Drawing Sheets
